Mo.

Application December 26, 1935, Serial No. 56,213

4 Claims. (Cl. 128—303.11)

This invention relates to electromedical instruments of the character used in radio frequency diathermy and in the nature of a prostatic electrode that is employed in connection with electrical devices of the well known type.

One of the important aims of this invention is the provision of an electromedical instrument, having as a part thereof, a body of material that is pervious to radio frequency waves, yet 10 pervious to electric currents, and which has housed therein, specially formed electrical current conducting elements to the end that the instrument might be used internally without directly subjecting tissue to electrical currents as 15 the same is acted upon by heat generated by the radio frequency waves.

A yet further object of this invention is to provide an electrode of the aforementioned character, with structure especially adapted for receiving a thermometer after the electrode is in place in the patient so that the exact temperature at the innermost part of the electrode might be 20 always determined without removing the instrument.

An even further object of this invention is the provision of an electromedical instrument having an undulated, tubular body and removable nipple at the end thereof, both of which are formed of insulating material and within which 25 is disposed a longitudinal tube, having at one end a removable, hollow, spherical electrode member that may be easily replaced simply by removing the nipple aforementioned.

Other objects of this invention and advantages 30 gained from the use thereof will become apparent during the course of the following specification, referring to the accompanying drawing, wherein:

Figure 1 is a longitudinal, central, sectional view through an electromedical instrument embodying this invention.

Fig. 2 is an end elevation of the same.

Fig. 3 is a cross section through the instrument, taken on line III—III of Fig. 1.

Fig. 4 is an enlarged, fragmentary, side elevation of the forward end of the instrument, with the nipple removed, and,

Fig. 5 is a cross section through the instrument, taken on line V—V of Fig. 4.

Heretofore electromedical treatments have usually employed metallic current-conducting materials in direct contact with the tissue of the organ being treated. In the use of radio frequency apparatus, the internal electrode, such as the one contemplated by this invention, is as-

sociated with an external electrode, not here shown, and radio frequency waves pass from one of said electrodes to the other through the tissues of the organs being treated, and as a result of such passage, heat is generated and an 5 appreciable rise in temperature is effected. It is desirable to maintain this temperature within a fixed, predetermined range and, accordingly, the use of a thermometer which will allow the attendant to determine the exact temperature at 10 the zone of greatest activity is desirable.

The electromedical instrument embodying the preferred form of this invention is adapted only for use in radio frequency diathermy and the combination of elements shown in the drawing 15 and hereinafter described, is suitable specifically for such treatment.

In the drawing, the numeral 8 represents a tubular body formed of insulating material such as Bakelite or other similar well known phenolic 20 derivatives and said body is hollow throughout its length and formed so that the exterior surface thereof is undulated to prevent a series of alternate, relatively small and larger transverse, spaced-apart diameters. Flange 10 formed integrally with body 8 limits the inserting action 25 and serves to seal the mouth of the orifice through which the undulated portion of body 8 has been inserted.

One end of body 8 is provided with a reduced 30 neck 12 that is externally screw-threaded as illustrated in Fig. 4. A nipple 14, having internal screw-threads thereon engages screw-threads of neck 12 so that nipple 14 is removably associated with body 8 and the outer contour of the instrument at the line of connection is smooth and uninterrupted. The form of nipple and body, 14 35 and 8, respectively, is as shown in Fig. 1, to the end that insertion might be accomplished with ease and without discomfort to the patient.

The other end of body 8 has a thickened portion 16 integral therewith and a branch 18 continues outwardly at an angle therefrom to contain metallic tubular branch 20 that is in electrical contact with tube 22 that extends longitudinally through body 8. This tube 22 conducts current and forms a part of the electrical circuit of the instrument and apparatus with which it is employed. A suitable tip 24 on the end of wire 26 is moved into branch 20 and secured in 45 place by thumb screw 28 when the instrument is in use.

The end of tube 22 adjacent nipple 14 is extended into a hollow, spherical metallic electrode 50 55 and removably secured thereto by a cross pin

or similar medium 32. This pin should be removable so that the sphere 30 might be replaced or interchanged if desired, and accordingly, pin 32 is provided with screw-threads 34 which engage the internal screw-threads of opening 36 formed in sphere 30. The openings 38 formed in opposed relation through the wall of tube 22 are not screw-threaded and permit the snug sliding of pin 32. Opening 40 provided in the wall of sphere 30 in opposed relation to opening 36 is likewise plain to permit the insertion of pin 32 and a socket 42 created in the end of pin 32 permits the use of a small tool for manipulating the pin to and from the assembled position.

When tube and sphere 22 and 30 are in place within body 8, a portion of both extend beyond the end of neck 12 so that pin 32 might be removed to exchange sphere 30 for another without removing tube 22. Manifestly, removing nipple 14 will permit withdrawing of the entire assembly, including tube 22, and sphere 30, or merely removing pin and sphere from association with tube 22.

A thermometer 44 may be inserted into tube 22 when the instrument is in place and during treatment. The bulb portion of thermometer 44 will lie within sphere 30 and the temperature at that point will always be determinable by observing the graduated scale 46 that is on that portion of thermometer 44 projecting from tube 22.

The form of metallic electrode 30 insures that the instrument will always be positioned in the most effective manner. It will be unnecessary to manipulate the instrument and hold the same in a certain position merely to inter-relate the internal and external metallic electrodes of the radio frequency circuit. Since this instrument is particularly useful in the treatment of prostate gland troubles, the value of the form of electrode 30 and its association with other parts of the instrument is even greater enhanced.

Manifestly, the circuit over which the radio-frequency oscillations are delivered to the patient includes an external electrode in contact with a selected part of the body, the internal electrode 30, the generator and that part of the body of the patient disposed between the external and internal electrodes. Suitable conductors (wires) connect the generator with the two aforesaid electrodes.

While the preferred embodiment of the invention has been illustrated and described, it is understood that many changes and modifications might be made without departing from the spirit of the invention or scope of the appended claims.

Having thus described the invention, what is claimed as new and desired to be covered by Letters Patent, is:

1. An electromedical instrument of the character described comprising a tubular body of electrical current insulating material; a nipple of like material in screw-threaded engagement with and closing one end of the said body; an apertured, metallic, hollow, spherical electrode within the body adjacent the nipple; and a metallic tube extending from within the said electrode through the said aperture to the other end of said body, said spherical electrode being removably secured to said tube for convenient replacement when the said nipple is detached. 5 10

2. An electromedical instrument of the character described comprising a tubular body of electrical current insulating material; a nipple of like material in screw-threaded engagement with and closing one end of the said body; an apertured, metallic, hollow, spherical electrode within the body adjacent the nipple; and a metallic tube extending from within the said electrode through the said aperture to the other end of said body, said body being undulated to provide alternate small and larger transverse spaced-apart diameters, the said electrode having an outside diameter substantially the same as the inside diameter of the body at one of the larger diameters and being positioned within the body at one of the larger diameters and at the zone of connection between nipple and body, thereby preventing longitudinal movement of the tube and electrode within the body when the nipple is in place. 15 25 30

3. In an electromedical instrument of the character described, a hollow body of material pervious to radio frequency waves and impervious to electrical currents; a hollow, spherical, metallic electrode housed within said body; a hollow metallic tube extending longitudinally along the said body in communication with the electrode; and a thermometer within the tube 40 having the bulb portion thereof extending into said electrode. 35 40

4. An electromedical instrument of the character described comprising a tubular body; a nipple removably secured to the body to close one end thereof; a hollow, spherical electrode, provided with an opening, within the tubular body adjacent the end thereof closed by said nipple and having a portion thereof extending outwardly from the said body when the nipple is removed; a tube of conductive material within the body extending longitudinally therethrough and having one end projected into the said electrode through the opening; and a pin removably securing together said electrode and the tube, said pin being in the portion of the electrode outside the body to permit removal thereof when the nipple is removed from normal position. 45 50 55
